UNITED STATES PATENT OFFICE.

JOHN J. STARKS, OF KANSAS CITY, MISSOURI, ASSIGNOR TO THE STARKS MANUFACTURING COMPANY, OF KANSAS CITY, MISSOURI, A CORPORATION OF MISSOURI.

STAINING AND DRYING MACHINE.

Application filed May 10, 1924. Serial No. 712,253.

To all whom it may concern:

Be it known that I, JOHN J. STARKS, a citizen of the United States, residing at Kansas City, in the county of Jackson and 5 State of Missouri, have invented certain new and useful Improvements in Staining and Drying Machines; and I do declare the following to be a full, clear, and exact description of the invention, such as will enable 10 others skilled in the art to which it appertains to make and use the same, reference being had to the accompanying drawings, and to the figures of reference marked thereon, which form a part of this specification.

This invention relates to shingle staining and drying machines, the primary object being to provide an improved machine provided with a stain reservoir and a receptacle 20 or holder for receiving shingles and submerging them in the liquid in the reservoir to permit them to absorb stain or the like and to then remove the shingles from the liquid and eliminate excess liquid before the 25 shingles are removed from the machine.

Machines for staining shingles have been used prior to my invention but my invention contemplates an improved form of shingle staining machine so constructed that a comparatively large number of shingles can be stained in a given time and with the illustrated embodiment of my invention, a relatively small machine may have a capacity of approximately four hundred bundles per 35 eight hour day.

The novel construction of the invention will be understood by reference to the following description in connection with the accompanying drawings, in which—

40 Fig. 1 is a perspective view of a shingle staining machine constructed in accordance with my invention, and

Fig. 2 is a vertical longitudinal sectional view through the same.

45 The illustrated embodiment of my invention includes a tank or receptacle 1 of sufficient capacity and strength to contain an adequate amount of liquid stain indicated at

2. The level of the liquid should be slightly 50 below the top of the tank 1, the upper portion of the tank having an outwardly disposed circumferential flange 3 to support the yoke or frame 4 which rests upon it and which is secured by means of bolts 5 or similar fastening devices.

In the bottom of the tank 1 is a step bearing 6 to receive a centrally located vertical shaft 7 which is mounted not only in the step bearing 6 but also in the bearings 8 and 9 carried by the yoke frame 4. The bearings 8 and 9 are split bearings to permit the ready installation and removal of the vertical shaft 7.

The vertical shaft 7 carries a mitre gear 10 driven by a complementary mitre gear 11 65 on shaft 12 which may be driven by any suitable means as for example by a belt 13 on pulley 14 carried by the shaft 12, the belt 13 being driven by any suitable power medium. Keyed or otherwise secured to the 70 shaft 7 is a propeller form of agitator 15 located adjacent to the bottom of the tank and adapted to rotate with the shaft to act as a stirrer to maintain the pigment of the stain for suspension. 16 is a sleeve on shaft 7 75 and rigid with the sleeve is a shingle holder or cage 17 having one or more doors 18 suitably fastened so that shingles may be introduced into the cage 17 and conveniently removed therefrom.

In actual practice I prefer to so construct the cage that there will be two sets of doors, each opposite the other, although the number of doors employed in all instances is not important, however if the cage is provided 85 at opposite sides with doors, the introduction of the shingles into the cage and the removal therefrom is facilitated.

At the upper end of the sleeve 16 is a clutch cone 19 which slides with the sleeve 90 on the shaft 7 and which is adapted to engage the cone socket or female member 20 keyed to shaft 7. The cage is adapted to be raised and lowered by a bridge member or bar 21 provided with a bearing in which 95 the sleeve 16 rotates. The bridge bar 21 is adapted to be raised and lowered by two chains 22 and 23 fastened to the pivoted brake levers 24 and 25, the toes of which are adapted to engage the pins 26 and 27 of a 100 friction brake disk 28 loosely mounted about the sleeve 16 but carried with the bridge bar 21.

The brake levers 24 and 25 are provided with slots 29 and 30 receiving pins 31 and 32 105 on the bridge bar and the heels of the levers are spring pressed by expansion springs 33 and 34 on spring rods 35 and 36, the headed lower ends of which abut against the abutments 37 and 38 carried by the bridge bar 110

21. Therefore it will be seen that when the weight of the cage and the bridge bar is carried by the chains 22 and 23, the springs will be compressed, the toes of the lever will be out of contact with the pins 26 and 27 so that the friction disk 28 will be out of contact with the clutch cone 19. Consequently when the clutch cone 19 is moved into the socket 20, the shaft will rotate the sleeve 16 and with it the cage.

10 In order to effect the raising and lowering of the bridge bar and cage, I have shown the chains 22 and 23 fastened to the sheaves 39 and 40 on the shaft 41 mounted in bearings 42 and 43 carried by the frame 4. The shaft 41 also carries a relatively large sheave 45 to which is secured a chain or flexible connection 46 carrying at its lower end a counterpoise or weight 47 to counterbalance the bridge bar shingle receiving cage or holder, therefore little power will be required to elevate or lower the cage.

15 In order to elevate or lower the cage, I have shown a sprocket 50 on the shaft 41 around which a chain 51 passes, the opposite end of the chain passing around a sprocket 52 on crank shaft 53 provided with a handle crank 54 so that by turning the shaft 53 in either of two directions, the cage 20 can be raised or lowered and in order to hold the cage in any elevated position, I provide a ratchet wheel 55 on shaft 53 to be engaged by a dog 56, see Fig. 1. A chain 30 tightener 57 may be employed if desired.

35 Mounted on the receptacle 1 is a counterpoised foot or pedal lever 58 having a rod connection 59 with a bell crank lever 60 mounted on shaft 61, the shaft 61 carrying a detent or dog 62 to engage under the end 40 of the bridge bar 21. A similar dog 63 is pivoted at 64 to the frame and it is provided with a crank 65 connected to a reverse motion lever 66 pivoted to the frame at 67, the connection being effected through a link 45 rod 68, the reverse motion lever 66 being connected to the bell crank 60 through a link 69.

50 Carried by the top of the receptacle 1 and by the frame 4 is a circumferential wall 70 provided with an opening 71 adapted to be closed by a sliding door or gate 72 but having sliding movement so that access can be had to the cage to introduce or remove shingles therefrom.

55 When the parts are assembled the operator can turn the crank 54 to raise the bar 21 and with it the shingle carrier or cage. The cage and bar can be raised until the ends of the bar 21 are in position to be supported by the hook shaped detents 62 and 63 whereupon the ends of the bar 21 will ride over the hooked ends of the detent 62 and 63 and rest upon the hooked ends.

60 If the door 72 is opened and the doors 18 65 of the cage are opened, an appropriate num-

ber of shingles can be introduced into the cage, then the doors 18 will be closed, the door 72 closed and the operator will press upon the pedal 58 to cause the detents 62 and 63 to move from bridge bar engaging position to bridge bar releasing position. By turning the crank 54 in a clockwise direction, the chains 22 and 23 will unwind from the sheaves 39 and 40 to allow the bridge bars to move downwardly to a position to submerge the cage or shingle holder, the shaft 7 turning this time, may be rotated without rotating the cage. When the cage reaches the lower position shown in Fig. 2, the stain will enter through the wire mesh of the screen-like walls and be absorbed by the shingles. All the while the stain will be agitated by the stirrer or agitator 15, then the operator can turn the crank in a clockwise direction to cause the shaft 41 to turn the sheaves 39 and 40 to wind the cables or chains 22 and 23 raising the bridge bar until the clutch cone 19 comes into contact with the rapidly revolving socket 20 on shaft 7. When the clutch cone 19 engages the clutch socket 20, the cage will partake of the rotative movement of the constantly rotating shaft 7 and will rotate with it at a rapid rate to throw off by centrifugal force any excess liquid, the excess liquid being thrown against the wall 70 surrounding the space above the liquid and thereby forming a drying chamber.

60 While the cone 19 is in engagement with the clutch socket 20, the ends of the bar 21 will be supported by the detent members 62 and 63. After the shaft has rotated the cage a sufficient length of time, the operator may slack up chains 22 and 23 by a reverse turn on crank 54 so that the springs 33 and 34 can force the toes of the levers 24 and 25 against the pins 26 and 27 to cause the brake 28 to engage the recessed portion of the cone 19 and since the collar 28 has an up and down movement but no rotative movement, it will be apparent that the cage will suddenly come to rest so that access thereto may be had. The shingles may now be removed in a relatively dry state devoid of excess moisture because this has been centrifugally removed within the space enclosed by the wall 70. A new batch of shingles will now be introduced into the cage and the cage can be submerged and be subjected to the violently agitated liquid in the tank which has been described above until a sufficient length of time has elapsed, whereupon the cage will again be raised and the cycle of operations above described will be repeated.

110 While I have described the device as particularly applicable for use in staining shingles, I do not wish to be limited to the device as a shingle staining machine for obviously the invention would operate in identically 115 120 125

the same manner as described irrespective of the contents of the cage.

What I claim and desire to secure by Letters-Patent is:

- 5 1. A staining machine comprising a tank, a vertical rotatable shaft in the tank, an article holder loosely sleeved upon the shaft, means for raising and lowering the article holder and means for connecting the article holder to the shaft in its raised position to cause the article holder to rotate with the shaft.
- 10 2. A staining machine comprising a liquid containing tank, a vertical rotatable shaft in the tank, an article holding cage loosely sleeved upon the shaft, an elevating bar connected to the sleeve for raising and lowering the cage and clutch members for connecting the cage to the shaft when the cage is raised by the bar above the level of the liquid in the tank so that the rotation of the shaft will rotate the cage to throw off moisture from the articles in the cage by centrifugal force.
- 15 3. A shingle staining machine comprising a liquid tank, a vertical shaft rotatable in the tank, an agitator carried by the shaft, a shingle cage sleeved on the shaft above the agitator and carrying a clutch member, an elevator for raising the cage, a clutch member keyed to the shaft to engage the clutch member on the cage in its raised position and a wall on the tank above the liquid level.
- 20 4. A shingle staining machine comprising a liquid tank, a shaft rotatable in said tank, a step bearing in the bottom of the tank upon which the shaft rests, a frame carried by the tank for supporting the upper portion of the shaft, a clutch member rigid on the shaft, a shingle cage movable on the shaft into and out of engagement with the clutch member and means for raising and lowering the cage.
- 25 5. A shingle staining machine comprising a liquid tank, a shaft rotatable in said tank,

a step bearing in the bottom of the tank upon which the shaft rests, a frame carried by the tank for supporting the upper portion of the shaft, a clutch member rigid on the shaft, a shingle cage movable on the shaft into and out of engagement with the clutch member and means for raising and lowering the cage, said means comprising a bar, a shaft above the bar, sheaves on the shaft and flexible connections between the sheaves and the bar.

6. A shingle staining machine comprising a liquid tank, a cage in the tank for containing shingles, means for raising and lowering the cage, a clutch member above the liquid level of the tank, a clutch member on the cage engageable with the first named clutch member when the cage is raised, means for rotating the first named clutch member and a brake carried by the means for raising and lowering the cage to stop rotation of the cage when the two clutch members are disengaged.

7. A shingle staining machine comprising a liquid containing tank, a shingle carrying cage in the tank, a bar for raising and lowering the cage, detents above the tank for supporting the bar in its raised position, a rotatable clutch member above the liquid level of the tank and a clutch member carried by the cage for engagement with the rotatable clutch member.

8. A shingle staining machine comprising a liquid containing tank, a shingle carrying cage in the tank, a bar for raising and lowering the cage, detents above the tank for supporting the bar in its raised position, a rotatable clutch member above the liquid level of the tank and a clutch member carried by the cage for engagement with the rotatable clutch member, and means for preventing rotation of the cage in its lowered position.

In testimony whereof I affix my signature.

JOHN J. STARKS.
